US00D932280S

(12) **United States Design Patent** (10) **Patent No.:** **US D932,280 S**
Garcia (45) **Date of Patent:** **** Oct. 5, 2021**

(54) **LOCKING PIN**(71) Applicant: **Coulter Ventures, LLC.**, Columbus, OH (US)(72) Inventor: **Nicolas Garcia**, Centerburg, OH (US)(73) Assignee: **Coulter Ventures, LLC.**, Columbus, OH (US)(***) Term: **15 Years**(21) Appl. No.: **29/765,483**(22) Filed: **Jan. 8, 2021****Related U.S. Application Data**

(63) Continuation of application No. 29/736,384, filed on May 29, 2020, now Pat. No. Des. 909,176, which is a continuation of application No. 29/667,362, filed on Oct. 19, 2018, now Pat. No. Des. 885,864.

Product listing for Rogue Monster Plate Storage Pin from <https://web.archive.org/web/20170423182638/http://www.roguefitness.com/rogue-monster-plate-storage-pin>, dated Apr. 23, 2017.

(Continued)

Primary Examiner — Steven J Czyz(74) *Attorney, Agent, or Firm* — Banner & Witcoff, Ltd.(57) **CLAIM**

The ornamental design for a locking pin, as shown and described.

DESCRIPTION

FIG. 1 is a top, front, right perspective view of a locking pin showing my new design;

FIG. 2 is a right side view thereof;

FIG. 3 is a left side view thereof;

FIG. 4 is a top view thereof;

FIG. 5 is a bottom view thereof;

FIG. 6 is a front view thereof; and

FIG. 7 is a rear view thereof; and,

FIG. 8 is a top, front, left perspective view of the locking pin shown in use with environment.

The broken lines depict portions of the article and environment that form no part of the claimed design.

1 Claim, 5 Drawing Sheets(56)
